W. T. DITCHAM

WIRELESS TRANSMITTER

Original Filed Dec. 18, 1920

Inventor

W.T. DITCHAM

By his Attorney, *Ira J. Adams*

UNITED STATES PATENT OFFICE.

WILLIAM THEODORE DITCHAM, OF LEBANON PARK, ENGLAND, ASSIGNOR TO RADIO CORPORATION OF AMERICA, A CORPORATION OF DELAWARE.

WIRELESS TRANSMITTER.

Original application filed December 18, 1920, Serial No. 431,582. Patent No. 1,454,598, dated May 8, 1923. Divided and this application filed February 8, 1923. Serial No. 617,894.

To all whom it may concern:

Be it known that I, WILLIAM THEODORE DITCHAM, a subject of Great Britain, residing at "Kildary," Lebanon Park, in the 5 county of Middlesex, England, have invented certain new and useful Improvements in Wireless Transmitters, of which the following is a specification accompanied by drawings.

10 The object of this invention is to provide an improved valve transmitter in which the transmission of the interfering noises, known as key clicks, may be avoided and the valves may be relieved of the full load during the spacing period of the Morse characters.

This application is a division of my application Serial No. 431,582 filed December 18, 1920 for wireless transmitters now 20 Patent No. 1,454,598, patented May 8, 1923.

The above identified application discloses a system wherein an oscillating valve is arranged to be energized from an alternating current source, the alternating current being 25 rectified before being impressed across the plate and filament of the valve.

The invention claimed in the said application comprises providing in the alternating current supply line an impedance or 30 choke coil of such value that the valve will oscillate at substantially the same frequency regardless of whether the impedance or choke coil is in circuit or short circuited. A key is provided for short-circuiting the 35 said impedance or choke coil. The operation of the invention is as follows:

When the key is open the impedance or choke coil is connected in the alternating current supply line and consequently the 40 tube will oscillate but will not supply sufficient power to transmit to any distance. However, when the key is closed, short-circuiting the impedance or choke coil, the valve will oscillate with full power and 45 thereby transmit signals. The modification covered by this application is illustrated in the single figure of the accompanying drawing.

It is an object of the invention herein 50 claimed to provide means for operating the tube from a D. C. source, such as a D. C. generator designated as 9 in the drawing.

In the supply line from this generator I provide a resistance 7 of such value that when it is in circuit the tube will continue 55 to oscillate feebly but at substantially the same frequency as before. I provide key 8 for signaling by short-circuiting this resistance. The valve 5 is coupled to an antenna 1 by means of coils 2 and 3, the antenna being grounded in the usual manner. The operation of my system is believed to be obvious from the drawing and specification and no detailed description thereof will be given. 65

Having described my invention, what I claim is

1. In a wireless transmitter the combination of an oscillating valve, a circuit containing a source of direct current supply for 70 said valve, and signaling means for varying the amplitude of the oscillations of said valve while maintaining a frequency constant, said signaling means comprising a resistance interposed between said source of supply and said valve and an interrupter for short circuiting said resistance. 75

2. In a wireless transmitter, the combination of an oscillating valve, a circuit containing a source of direct current supply for 80 said valve, a resistance interposed between said source of supply and said valve, said resistance being of such value that the valve will oscillate at substantially the same frequency regardless of whether said resistance 85 is included in the circuit and means for short-circuiting said resistance.

3. In a wireless transmitter, the combination of an oscillating valve, having a filament, grid and plate electrodes, a circuit 90 connecting the filament and the grid electrode, a second circuit connecting the plate and filament electrodes coupled to the first circuit, a source of direct current supply in the plate filament circuit of said valve, 95 signaling means for varying the amplitude of the oscillations of said valve while maintaining the frequency constant, said signaling means comprising a resistance interposed in the plate circuit of said valve and 100 an interrupter for short circuiting said resistance.

WILLIAM THEODORE DITCHAM.
